(57) **CLAIM**

The ornamental design for a dosage cap, as shown and described.

DESCRIPTION

FIG. 1 is a front perspective view of a dosage cap in accordance with the new design;

FIG. 2 is top plan view thereof; and,

FIG. 3 is a front elevational view thereof, left-side, rear, and right-side elevational views being identical.

The bottom plan view of the dosage cap is not shown in the drawings or described in the specification and, therefore, forms no part of the claimed design.
